Inventor:
Timothy F. Taft

United States Patent Office.

TIMOTHY F. TAFT, OF SHREWSBURY, ASSIGNOR TO AUGUSTUS RICE, OF WORCESTER, MASSACHUSETTS.

Letters Patent No. 65,138, dated May 28, 1867.

IMPROVED MACHINE FOR CUTTING SHEET OR BAR METAL.

The Schedule referred to in these Letters Patent and making part of the same.

Be it known that I, TIMOTHY F. TAFT, of Shrewsbury, in the county of Worcester, and Commonwealth of Massachusetts, have invented a certain new and useful Improvement in Machines for Cutting Sheet and Bar Metal, and known as "Lock-Shears;" and I do hereby declare that the following is a full, clear, and exact description of the same, reference being had to the accompanying drawings, forming a part of this specification, in which—

Figure 1 represents a perspective view of a pair of "lock-shears" with my improvement applied thereto.

Figure 2 represents a front view of the same; and

Figures 3, 4, 5, and 6 represent different views of the projections J J, which are cast upon the main part or frame A of the machine.

To enable others skilled in the art to which my invention belongs to make and use the same, I will proceed to describe it more in detail.

The nature of my invention consists in the use, in combination with a connecting-bolt, of two arms J J, cast upon the main piece or frame A A, one on the part called the upper jaw, and one on the part called the lower jaw, (see figs. 1 and 2,) for the purpose of giving greater strength when cutting bar metal.

"Lock-shears" seldom if ever break when cutting sheet metal, but most always when cutting bar metal. I have proved by experiment that a pair of shears will sustain one-third more pressure by being tied through the arms J J by means of bolt K than without such an arrangement. Boiler-makers, blacksmiths and others that have occasion to use shears, are much better satisfied with the "lock-shears" with the above improvement than when made without it.

In the drawings, the part marked A A is the main piece or frame of the machine, and combines or embraces the upper as well as the lower jaw. The dotted lines O O indicate the point of union between the jaws. One side of the upright part of the piece A is cored or recessed out to receive the eccentric D upon the main shaft C and pitman E and slide F, as fully indicated in dotted lines, fig. 1; the pitman E being slipped upon the eccentric, and also connected to slide F by a pin, P. The parts above described are protected from dirt and retained in proper position by a face-plate, B, which is fastened to the side of the part A by bolts H. G is the lower or stationary blade, which is attached to the lower-jaw by bolts; and G' is the upper or sliding blade, which is attached by bolts H' to the slide F. The blades G G' are so arranged that the face of the upper blade G' always works close to the stationary blade G. The lever-shank M is fastened to the main shaft C so as to work upon the back side of the frame A. Lever N is inserted in the shank M, and is used to operate the shears with hand-power is employed. The arms J J are tied or connected by bolt K, the bolt being passed through holes in the arms, and then nut L screwed on to tighten up the bolt, as fully indicated in the drawings.

The operation is as follows: The end of the sheet of metal to be cut is passed between the cutters or blades G G', and the piece or strip which is being cut off is bent down slightly by the operation, and slides freely under the angle formed by the bottom of the upper jaw, indicated by the lower dotted line O, while the strip or sheet of metal held in the hand, and from which the strip or piece is being cut, slides freely over the upper surface of the lower jaw, indicated by the upper dotted line O, which is on a line with the top of the stationary blade or cutter G, so that strips of any desired width and length can be cut, one part passing back of the lock, while the other part passes in front of the lock.

Having described my improvement in "lock-shears," what I claim as new, and of my invention, and desire to secure by Letters Patent, is—

The application to the "lock-shears" above described of two arms, J J, with bolt K and nut L, or their equivalents, substantially as described.

TIMOTHY F. TAFT. [L. S.]
